CLAIM

The ornamental design for a showerhead, as shown and described.

DESCRIPTION

FIG. 1 is a perspective view of a showerhead showing my design;

FIG. 2 is a front elevation view;

FIG. 3 is a side elevation view;

FIG. 4 is a top plan view; and,

FIG. 5 is a bottom plan view.

The broken lines indicate portions of the showerhead that form no part of the claimed design.
